UNITED STATES PATENT OFFICE.

WILLIAM SPARKS, OF JACKSON, MICHIGAN, ASSIGNOR TO THE SPARKS-WITHINGTON COMPANY, OF JACKSON, MICHIGAN, A CORPORATION OF OHIO.

RADIATOR.

Application filed September 25, 1917. Serial No. 193,079.

To all whom it may concern:

Be it known that I, WILLIAM SPARKS, a citizen of the United States, and resident of Jackson, in the county of Jackson, in 5 the State of Michigan, have invented new and useful Improvements in Radiators, of which the following, taken in connection with the accompanying drawings, is a full, clear, and exact description.

10 This invention relates to radiators of the type particularly designed for use in the cooling of internal combustion engines in which the water circulating tubes are separated by a spacer so fashioned and arranged in conjunction with the water tubes as to provide a cellular structure.

The object of the invention is to provide a radiator of the above type of increased efficiency in cooling a circulating fluid, and 20 preferably this is effected by providing the spacer with a multiplicity or plurality of perforations or openings permitting communication between adjacent cellular units of the radiator structure, and by permitting 25 direct contact of the air passing through the cellular units with substantially the entire exterior surface of the water tubes.

Other objects and advantages will appear from the following description, taken in 30 connection with the accompanying drawings, in which—

Figure 1 is a front view, partially in section, of a portion of a radiator illustrative of the invention herein.

35 Figure 2 is a horizontal section through a portion of such a radiator.

Figure 3 is a perspective view of a portion of the spacer.

The radiator shown comprises a series 40 of vertically arranged water tubes —1— of corrugated form, each corrugation at the vertical marginal edges of the tube in this specific illustration constituting three sides of a hexagonal cell.

45 The upper and lower ends of the tubular cells may be connected in the usual manner to upper and lower headers or tanks, respectively, (not shown) in any suitable or well known manner, not necessary to herein 50 illustrate or further describe.

Each water tube —1— is separated from the adjacent water tube or tubes by a spacer —2—, likewise, in this specific illustration, of corrugated form, and each corrugation 55 at the vertical marginal edges of the spacer

constituting three sides of a hexagonal cell, so that when the spacer is placed between two adjacent water tubes two vertically disposed rows of hexagonal cells are formed, one-half of each cell of each row being 60 above or below, or both above and below, one-half a cell of the adjacent vertical row of cells.

The intermediate portion of the spacer and the intermediate portions of the water 65 tubes need not be corrugated with that exactness used in shaping the marginal edges of both the spacer and the water tubes, as the attachment of the intermediate portion of the spacer to the intermediate portions 70 of the water tubes is not necessary, and in practice is not generally effected.

The marginal portions of the water tubes and the spacer which lie in contact, in this illustration in substantially vertical planes, 75 may be secured together in any suitable manner, as by solder or the like, to constitute a unitary cellular structure.

The spacer, as best shown in Figure 3, is provided at each edge within the marginal 80 portions —3— that are shaped with exactness, with oppositely offset loops —4— and —5—, respectively. The loops —4— are slit at opposite sides from a depressed portion of a corrugation and are then offset in the opposite direction from the portion of the corrugation from which slit, while the loops —5— are slit at opposite sides from a raised portion of the corrugation and are offset 85 in the opposite direction so that these loops —4— and —5— extend within corrugations of different water tubes, the loop —4— extending from one side of the spacer —2— while the loop —5— extends from the opposite side of the spacer.

90 The portion of the spacer intermediate the loops —4— and —5— is provided with a multiplicity of perforations or openings —6—, sufficient in number to materially interrupt the continuity of the spacer member 95 and to permit free passage of the air from one cellular unit in the completed radiator structure to adjacent cellular units. Further, these openings, as well as the openings provided by the loops —4— and —5—, permit 100 direct contact of air passing through the cells with the portions of the water tubes with which the spacer member ordinarily lies in contact. By forming the spacer member with a multiplicity of openings, permit- 105 110

ting free passage of air between the adjacent cellular units of the structure, the efficiency of the radiator in cooling the circulating fluid is materially increased.

6 Although I have shown and described one particular construction of radiator and one particular form and arrangement of the cellular structure, I do not desire to limit myself to the same, as the invention herein is
10 adapted for application to many and various forms of radiators irrespective of the exact form and arrangement of the cells, and I do not desire to limit myself to the exact form of spacer member here shown, or to the
15 shape or arrangement of the perforations or openings therein, as many changes may be made in each and all of the same without departing from the spirit of this invention as set forth in the appended claims.

20 What I claim is:—

1. A radiator comprising a plurality of water tubes, each tube formed of a pair of strips of metal bent into similar tortuous form and shape, and nested together, and
25 having their edges off-set and in contact, and their central portions spaced apart, a spacer between each adjacent pair of water tubes, said spacer formed of a strip of metal having its opposite edge portions accurately
30 shaped to the same form and outline as the edge of the strip constituting the water tubes, said spacer forming with said two adjacent water tubes two vertical over-lapping rows of cells, the said spacer constituting a
35 symmetrical one-half of the wall of each cell, and pairs of loops formed in connection with the spacer and positioned adjacent the respective accurate shaped edge portions thereof, and extending in opposite directions
40 from the said spacer in the said rows of cells and spaced from the walls of the water tubes.

2. A radiator comprising a plurality of water tubes, each tube formed of a pair of

strips of metal bent into similar tortuous 45 form and shape, and nested together, and having their edges off-set and in contact, and their central portions spaced apart, a spacer between each adjacent pair of water tubes, said spacer formed of a strip of metal 50 having its opposite edge portions accurately shaped to the same form and outline as the edge of the strip constituting the water tubes, said spacer forming with two said adjacent water tubes two vertical over-lapping 55 rows of cells, the said spacer constituting a symmetrical one-half of the wall of each cell, and pairs of loops formed in connection with the spacer and positioned adjacent the respective accurate shaped edge 60 portions thereof, and extending in opposite directions from the said spacer in the said rows of cells and spaced from the walls of the water tubes, the intermediate portion of said spacer between said loops provided with 65 a multiplicity of perforations.

3. In a radiator, a pair of tortuous water tubes, a spacer formed of a single strip of material having its opposite edge portions accurately shaped to the same form and outline as the water tubes, said spacer positioned between and forming with said water tubes two vertical over-lapping rows of cells and pairs of loops formed in connection with the spacer and positioned adjacent the respective accurate shaped edge portions and extending in opposite directions from the spacer into said rows of cells and spaced from the walls of the water tubes, and the intermediate portion of said spacer between 75 80 said loops being provided with a multiplicity of perforations.

In witness whereof I have hereunto set my hand this 18 day of Sept. 1917.

WILLIAM SPARKS.
